Primary Examiner — Manpreet S Matharu*Assistant Examiner* — Mojtaba Tehrani(74) *Attorney, Agent, or Firm* — Wood Herron & Evans LLP(57) **CLAIM**

The ornamental design for a wheel, as shown and described.

DESCRIPTION

FIG. 1 is a front left perspective view of the first embodiment of a wheel, showing my new design;

FIG. 2 is a front view thereof;

FIG. 3 is a left side view thereof, the right side being a mirror image thereof;

FIG. 4 is a front left perspective view of the second embodiment of a wheel, showing my new design;

FIG. 5 is a front view thereof; and,

FIG. 6 is a left side view thereof, the right side being a mirror image thereof.

In FIGS. 1-6, the broken line show environmental structure and form no part of the claimed invention. More, specifically, in FIGS. 1, 2, 5 and 6, the centrally located broken lines show wheel hub structure, including bolt holes.
